United States Patent Office

Des. 211,042
Patented May 14, 1968

211,042

CONDIMENT DISH

Willis A. Stageberg, 3141 Rhode Island Ave. S.,
Minneapolis, Minn. 55426

Filed July 27, 1967, Ser. No. 8,027

Term of patent 14 years

(Cl. D44—7)

FIG. 1

FIG. 2

FIG. 3

I claim:

The ornamental design for a condiment dish, as shown.
